US0D1091600S

(12) **United States Design Patent** (10) Patent No.: **US D1,091,600 S**
(45) Date of Patent: ** Sep. 2, 2025

- (54) **DISPLAY SCREEN OR A PORTION THEREOF WITH GRAPHICAL USER INTERFACE**
(71) Applicant: **Toontrack Music AB**, Umeå (SE)
(72) Inventors: **Magnus Dahl**, Umeå (SE); **Leif Holm**, Umeå (SE); **Erik Phersson**, Umeå (SE); **Anton Nordmark**, Umeå (SE); **Henrik Ekblom**, Umeå (SE); **Andreas Walfridsson**, Umeå (SE)
(73) Assignee: **Toontrack Music AB**, Umeå (SE)
(**) Term: **15 Years**
(21) Appl. No.: **35/520,838**
(22) Filed: **Mar. 18, 2024**
(80) **Hague Agreement Data**
Int. Filing Date: **Mar. 18, 2024**
Int. Reg. No.: **DM/236749**
Int. Reg. Date: **Mar. 18, 2024**
Int. Reg. Pub. Date: **May 10, 2024**
